UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF NEW YORK.

DRY-PIPE SPRINKLER SYSTEM.

Application filed June 22, 1923. Serial No. 647,172.

This invention relates to dry pipe systems for plural liquids such as may be used in automatic sprinkler fire extinguishing apparatus, discharging liquids operating by chemical reaction. Such systems employ two liquids, one of which is ordinarily an acid and the other an alkali, which react together immediately on mixing. For this reason and because the acid is corrosive it is especially desirable to employ the dry pipe principle, in which the pipes remain normally filled with air until a sprinkler opens from the heat of a fire, whereupon the reduction of air pressure automatically trips a valve for each liquid, to admit it to its system of piping leading to the sprinklers. In such cases it is highly desirable that both liquids, travelling through their respective systems, should arrive at the open head at the same instant, as the required effect is produced only by mixing, and as either alone may be seriously damaging to goods on which it may fall. It has, however, heretofore been found practically impossible to build two systems thus in parallel so that the valves will operate simultaneously. The present invention has for its object to provide means for the simultaneous operation of the separate valves controlling the liquids of such systems.

This object is accomplished by providing liaison means which may take the form of an operative connection between the two valves such that either may trip the other, or more, strictly, such that the tripping of either occasions the simultaneous tripping of the other. This is attained by providing a physical connection, which may be either mechanical or fluid in its nature. The particular style chosen for illustration is a fluid connection, applied to a well known type of differential valve comprising a single double-faced valve, in which the air face is larger than the water face so that the whole is maintained closed against the hydrostatic pressure of liquid by air at a lower pressure in the distribution piping system. Normally a fall in the latter, consequent upon the opening of a sprinkler head, results in the hydrostatic pressure driving the valves open when the air pressure gets down to below one-sixth of the liquid pressure.

In the specific type of invention herein set forth, the said connection is a passage providing for flow of fluid between the intermediate chambers of the two automatic dry pipe valves. Preferably this passage is in part identical with the passage which is customarily provided from the lowest point of each chamber to a drip valve which is normally open to atmosphere, and which contains a ball valve, that permits slow escape of either air or liquid, but which is rushed to its seat by any considerable flow that begins. Thus a single drip and its automatic ball valve serve for both intermediate chambers; and the two passages to the single drip valve together make a passage from either chamber to the other. When the air pressure in either distribution system falls low enough to cause the beginning of a valve-opening movement, the air-flap part of the valve, which has a flexible rubber edge, at first yields slightly without actually opening. But such slight yielding actually opens the liquid valve to a corresponding degree, it having metallic face and seat, and consequently a small flow of liquid begins, into its intermediate chamber and thence out through the drip pipe, thus closing the drip valve and cutting off the connection to atmosphere. Through the inter-chamber connection provided by the present invention, this liquid also flows into the intermediate chamber of the other valve. Thus in both intermediate chambers a pressure is quickly built up. This quickly overpowers the air pressure, both in the first system where the air pressure had fallen to the necessary amount, and in the second system where the air pressure may be assumed not yet to have fallen to the necessary amount, throwing both valves open practically simultaneously.

The opening of either valve releases a suspended plug in the intermediate chamber of that valve, which in falling closes the passage to the other valve chamber, preventing further transfer of fluid between the two systems. Although here illustrated only as it may be applied to differential valves, the invention is generic in character and may apply also to mechanical valves whose action depends on difference of leverage, in which case there may be, in one form, a

mechanical operating connection directly between the moving parts instead of the fluid operating connection between the intermediate chambers herein shown. Or, in the 5 case of such valves as operate by the falling of a weight, a single weight may be made to trip both valves. Or, in cases where each valve has its own weight, and has completely independent action, the weight in each 10 case being tripped by change of air system pressure on a diaphragm, there may be a fluid connection between the diaphragm chambers so that the falling of pressure in either is accomplished by equal fall in the 15 other. Or, there may be a single diaphragm connected with either or both systems of pipes but used in common by the weights or other devices by which the valves in the two systems are tripped. It is thus seen 20 that the invention may be applied in many and various embodiments. It is intended that the patent shall cover by suitable expression in the appended claims whatever features of patentable novelty exist in the 25 generic invention and in the specific application thereof herein disclosed. The other species above mentioned are set forth and claimed in three several other applications for patent, Serial Nos. 647,173; 647,174; and 30 647,175; filed coincidently herewith.

In the accompanying drawing:—

The single figure illustrates in elevation the application of the invention to pipes of a sprinkler system.

Referring to the drawing, 10 indicates a fusible strut in an automatic sprinkler of a well known or of any suitable type, having two parts 11 and 21 connected respectively to distribution pipes comprising laterals 12 40 and 22 leading from risers 13 and 23 which normally are filled with air under pressure held in by the valves 11' and 21' which the strut 10 maintains closed. As arranged heretofore, upon the fusion of the strut 10, as by heat from a fire, air issues from the valves 11', 21', reducing the pressure in both systems of piping until the dry pipe valves 14 and 24 operate automatically, admitting the respective liquids from the risers 15 and 45 25 to the distribution systems. It is the problem of the invention to provide so that emission of these liquids from the valves 11' and 21' shall begin as nearly simultaneously as possible. The piping being designed alike in the two systems, as has heretofore been the practice, it nevertheless has been found that differences of internal volume, of angle, of corrosion, or other causes, not wholly known, produce differences in the times at 50 55 which the dry pipe valves automatically are actuated.

It is one important feature of the invention to provide means by which the dry pipe valves shall act simultaneously. To this end, and in the embodiment here specifically

illustrated, the acting of one is retarded slightly, although perhaps imperceptibly, while the fluid material which might go to operate it is being shifted into the other valve, thereby supplying actuating fluid in 70 advance of that which normally would originate in that valve; and the two, thus prepared simultaneously, are actuated simultaneously by the overpowering pressure from that which was ready first, without the 75 second undergoing that slight delay which normally ensues during a period of balance after a valve is ready to be tripped. In the normal actuation of a valve of the type described, a reduction of air pressure in the 80 riser 23 and on air valve 24' permits liquid pressure on the valve 24'' to raise that valve a little due to flexure of the rubber edge portion 24^a of the valve 24' before actually separating from its seat. The slight resulting escape of liquid flows into the intermediate chamber 24'' which ordinarily is open to atmosphere through the pipe 30 and drip 31 containing a ball valve which permits slow escape of air or liquid but which closes 90 when a rush of fluid seeks escape. Ordinarily it has been customary to provide one such drip 31 with automatic valve with the intermediate chamber 24'' of each dry pipe valve of which those here referred to as a 95 whole by the numerals 24 and 14 are examples. In the present case, this drip is connected by the pipes 30 to the intermediate chambers of both valves, so that liquid flowing freely into one, as from the valve 24'' 100 in its incipient stage of opening, after incidentally closing the drip valve 31, flows on into the intermediate chamber of the other valve 14. In consequence, the continued escape of liquid past the valve 24'' piles up 105 pressure in the intermediate chamber of both valves 24 and 14 so that presently and simultaneously both air clappers are driven open, carrying with them the liquid valve clappers and letting the liquids into the two risers 110 simultaneously.

The quantity of liquid which thus passes over from one chamber to the other and the resulting foam gas formation is negligible. Further flow of liquid from one chamber to the other through passage 30 is prevented by the closing of both ends of the passage upon the opening of the dry pipe valves, there being a latch weight 38 in each casing; normally held up by the valve when closed, 115 which falls when the valve swings away from its seat and forces a plug into the entrance of the passage 30.

It is desirable for the perfect simultaneousness of action that there be a communicating passage as indicated at 32, between the risers 23 and 13, or elsewhere between the air portion of the two systems, so as to provide equality of air pressure on the two dry pipe valves. The drawing illustrates this 120 125 130

by showing compressed air supply into only one of the pipes, through valve 33, and thence into the other through passage 32; but it is obvious that this might be otherwise arranged, as by pumping from a common source into both.

Upon the opening of the valves 14 and 24 and the rush of liquids through the risers 13 and 23, a small quantity of liquid from each flows into the connection 32.

The gas formed at the place of meeting prevents further mingling of the liquids there; and the maintenance of this gas separator may be aided by providing the medial chamber 32' with partition turning up from the bottom, at whose top the gas tends to be trapped.

The drawing also illustrates how the invention may be applied with a dry pipe valve accelerator. Such apparatus of a known type is shown at 34, being connected with one of the systems at 35 and having a discharge pipe 36 leading to the inter-chamber pipe 30 and drain 31. Air pressure of the system enters the accelerator freely through the valve 34'; and conditions remain unchanged while air is being pumped into the system or during any relatively slow decrease of system pressure as by slight leakage; but when a sprinkler head opens, as at 11', with rapid decreasing of air pressure in the system the accelerator 34 performs its function by the opening of a valve within it which allows the air of the system to flow directly from 13 through 35 and 36 to pipe 30 whence it rushes into the intermediate chambers, builds up the pressure in both simultaneously so that air pressure is balanced on each air clapper and causes the hydrostatic heads to operate both dry pipe valves 24, 14, simultaneously. As the valve 37 indicates, the system may be used either with or without the accelerator 34, by opening or closing this valve.

The application of the invention equalizes the conditions of pressure in the intermediate chambers of the separate valves and brings both valves to the tripping point simultaneously. A substantially simultaneous start of flow in both systems is thus established, whereby both liquids reach the open sprinkler head at the same time wherever it may be.

I claim as my invention:

1. A fire extinguishing apparatus comprising a plurality of systems, providing for flow of different fluids which in combination make a fire extinguishing product; said systems having each a dry pipe valve and primary means for initiating the opening of that valve; combined with liaison means applied to the several dry pipe valves and causing them to coact in opening.

2. A fire extinguishing apparatus comprising a plurality of systems, providing for

flow of different fluids which in combination make a fire extinguishing product; said systems having each a dry pipe valve and primary means for initiating the opening of that valve; combined with unitary means applied to the several dry pipe valves for equalizing the operating influences on the said valves.

3. In a dry pipe system for plural liquids the combination with a dry pipe valve for each liquid, of operative connection between and at the said valves.

4. In a dry pipe system for plural liquids the combination, with a differential dry pipe valve for each liquid, of means for fluid connection between the intermediate chambers of the said valves.

5. In a dry pipe system for plural liquids the combination with a dry pipe valve for each liquid, of means for fluid connection between the air risers thereof close to the said valves.

6. In a dry pipe system for plural liquids the combination, with a differential dry pipe valve for each liquid, of a fluid pressure controlling device for the intermediate chamber of each valve and means whereby the fluid pressure thereby controlled is the same for said valves.

7. In a dry pipe system for plural liquids the combination, with a dry pipe valve for each liquid, of a device controlling and equalizing the tripping of said valves, and actuated by drop of fluid pressure in either system.

8. In a dry pipe system for plural liquids, the combination of a dry pipe valve for each liquid, having as an operating part a chamber wherein a pressure change may trip the valve, and means affording fluid communication and equalization of pressure between the said chambers of the several valves.

9. In a dry pipe system for plural liquids the combination, with a dry pipe valve for each liquid, of an accelerator connected to one of the distributing systems for its own actuation and connected operatively to both of the valves.

10. In a dry pipe system for liquids the combination, with a dry pipe valve for each liquid having differential areas exposed to air and liquid, and having an intermediate chamber between said exposed areas with an opening to atmosphere insufficient to pass more than a minor flow of liquid; of an accelerator connected to one of the distributing systems for its own actuation, and connected to said intermediate chambers to actuate their respective valves.

11. In a dry pipe automatic sprinkler system for plural liquids, the combination, with a dry pipe valve and distribution system for each liquid, and coacting discharge valves at each sprinkler, of means additional to the co-acting sprinkler valves for equalizing the

opening influences on the dry pipe valves whereby the said dry pipe valves operate substantially simultaneously.

12. In a dry pipe automatic sprinkler system for plural liquids, the combination, with a dry pipe valve and distribution system for each liquid, and co-acting discharge valves at each sprinkler, of means additional to the co-acting sprinkler valves for equalizing the opening influences on the said dry pipe valves.

13. In a dry pipe system for plural liquids the combination, with a dry pipe valve for each liquid, of means for fluid connection between the air risers thereof close to the said valves, said means including a chamber having a partition extending upward from its bottom, at whose top the gases, formed by the mingling of the liquids when flow occurs in the risers, are entrapped and thereafter maintain said liquids separated in the connection.

14. In a dry pipe system for plural liquids, the combination, with a pair of differential dry pipe valves having intermediate chambers, of a fluid connection between said chambers; a drain in said connection con-

stituting a vent to atmosphere from said chambers and valve therefor operative upon rush of fluid through said connection to 30 close said drain; and a plug in each said chamber adapted upon opening of its respective dry pipe valve to close the connection leading therefrom to the other intermediate chamber.

15. In a dry pipe system for plural liquids, the combination, with a pair of distribution systems, a pair of differential dry pipe valves therefor having a fluid connection between their intermediate chambers, and a drain and valve adapted upon rush of fluid to close said drain; of an accelerator discharging into said connection and having its own operating connection leading from one of the distribution systems beyond its dry pipe valve, 40 adapted upon sudden drop of pressure in said distribution system to transmit a rush of fluid to said connection and intermediate chambers whereby the dry pipe valves open 45 simultaneously.

Signed at Boston, Massachusetts, this 18th day of May, 1923.

ALBERT J. LOEPSINGER.
